AUTOMATICALLY OPERATED WATER
MOTOR

George W. Jacobs, New York, N. Y.

Application May 15, 1934, Serial No. 725,700

10 Claims. (Cl. 103—60)

This invention relates to an automatically operated water motor.

The object of the invention is the production of an automatically operated water motor, which is actuated by the energy of a running stream, whereby an elevated reservoir is automatically and intermittently filled with water.

The second object of the invention is the production of a water motor, comprising among its 10 elements a paddle wheel rotated by impact with a running stream, and which is automatically immersed into and drawn from said stream to intermittently operate pumping means to pump water.

15 In the accompanying drawings, Fig. 1 represents a plan view partly in horizontal section of the automatically operated water motor; Fig. 2 shows a section of Fig. 1 on the line 2, 2; Fig. 3 indicates a partial side view and section of Fig. 1 on the line 3, 3; Fig. 4 indicates an enlarged section of Fig. 3 on the line 4, 4; Fig. 5 shows a section on a reduced scale of Fig. 3 on the line 5, 5; Fig. 6 represents a section on an enlarged scale of Fig. 1 on the line 6, 6 and Fig. 20 7 shows an elevation partly in section of the water motor, with its appurtenances for a water supply and irrigating system.

The automatically operated water motor is shown supported on a float indicated in its 25 entirety by the numeral 20. The said float 20 comprises the longitudinal side walls 22, the deck 23 and the bottom wall 24. Between the deck 23 and the bottom wall 24 is indicated the buoyant chamber 30. The latter is indicated having the side walls 31, the converging front walls 32, which join in the peak 33, and the rear wall 34. Between the walls 22 and 31 are formed the longitudinal channels 35 having converging 30 inlets and the outlet openings 35a.

40 In the chamber 30 is indicated the well 36 comprising the side walls 37, the front wall 38 and the rear wall 39. In the bottom wall of the well 36, which is part of the wall 24, are shown a plurality of openings 40. Screens 41 and 42 are respectively provided for the top face and the bottom face of the bottom wall of the well. A pocket 45 extends downwardly from the deck 23, and is indicated having the front wall 46, the bottom wall 47, and the inclined rear wall 48. In the rear portion of the deck 23 are indicated a pair of openings 50. Curved deflecting strips 51 triangular in cross section, are fastened to the walls 22 and 31 of the channels 35 and wedge shaped deflecting strips 51a are fastened to the walls 24 of said channels. Longi-

tudinal splash boards 52 having the clearance openings 52a for the journal boxes 85 to be described, extend upwardly from the deck 23 at the inner edges of the openings 59 and inclined cross splash boards 53 join with the splash 5 boards 52.

From the front corners of the float 20, extend the similar fittings 54, vertically spaced from each other. From the peak 33 extend similar fittings 55, also vertically spaced from each other. From the fittings 54 extend the converging pipes 56 vertically spaced apart. From the fittings 55 extend the pipes 57, also vertically spaced from each other. The uppermost pipes 56 and 57 are connected by the fitting 59. The central pipes 56 and 57 are connected by the fitting 60 and the lowermost pipes 56 and 57 are connected by the fitting 61. The fittings 59, 60 and 61 are connected by the vertical piping 62.

Screens 63 are connected to the said converging pipes and to the said vertical piping. The screens with their appurtenances, constitute a fender to prevent débris entering the channels 35 to avoid injury to the motor. The housing 64 of the float 20 comprises the lower longitudinal beams 65 and the lower cross beams 66. Vertical posts 67, 68 and 68a extend up from the lower beams. Upper longitudinal beams 69 and upper cross beams 70 are provided for the housing. Inclined rafters 71 and the ridge pole 72 are provided for the roof of the housing 64. Posts 73 extend between the beams 70 and the ridge pole 72. Sheathing 74 is provided for the vertical walls of the housing and sheathing 75 is shown for the roof of said housing. A window 35 is indicated at 76 and a door is shown at 77. A pair of guides 80, each comprise the concentric arms 81, each with a radius struck from the center of the shaft 131 to be described. The arms are joined at their upper ends by the curved crown 82, and at their lower ends by the connecting member 83, which has integral therewith the flanges 84. The guides 80 are fastened to the deck 23. In the guides 80 are slidably positioned the elongated journal boxes 85. The latter each comprise the lower member 86 and the usual cap 87 bolted to the member 86. From each of the caps 87 extends the flange 88 and a bushing 89 is provided for each of said journal boxes 85. A driving shaft 92 is journaled in the 50 journal boxes 85. Chains 93 have each one end connected to one of the flanges 88 and their other ends are connected to the cross brace 94 and from the latter the chains 93 converge as shown in Fig. 1.

From the ridge pole 72 depends the journal bracket 95 having the guide roller 96 journaled therein, and the journal bracket 97 having the guide roller 98 journaled therein.

5 A controlling lifting bucket is indicated in its entirety by the numeral 102, and comprises side walls 103, the front wall 104, the rear wall 105 and the bottom wall 106. A bracket 107 extends from each of the side walls 103. An 10 overflow pipe 109 extends from the bottom wall 106. A chain 110 has one end connected to the chains 93 and leads over the guide rollers 96 and 98 and the other end of the chain 110 is fastened to the chain 111 which latter is fastened to the 15 brackets 107.

15 A controlling outlet valve 112 having the valve stem 113 with the disc handle 114 extends from the bottom wall 106 of the bucket 102 and coacts with an opening 115 in said wall 106. A bracket 20 116 extends from the wall 106 for the valve stem 113.

20 A power pump is designated in its entirety by the numeral 120 and is indicated having the cylinders 121, the connecting rods 122, the crank 25 123 and the crank shaft 125.

25 To the deck 123 are fastened a pair of journal boxes 130 for the worm shaft 131, which latter has fastened thereto the worm 132. Integral with one of the journal boxes 130 is indicated the 30 journal box 133, which is also fastened to the deck 23. One end of the crank shaft 125 is journaled in the journal box 133. The splash board 52 adjacent to the journal boxes 130 and 133 is slightly recessed for the same. A worm wheel 135 is fastened to the crank shaft 125 and is in 35 mesh with the worm 132. To the worm shaft 131 is fastened the spur gear 138, and to the driving shaft 92 is fastened the pinion 139 which is in mesh with the spur gear 138.

40 A pair of paddle wheels are each indicated in its entirety by the numeral 140. Each of said paddle wheels comprises the outer disc 141, the inner disc 142 and the central disc 143. Radial spokes are indicated having the blades 145 with 45 the bent up outer ends 146. Flanges 147 are integral with the blades 145 and their bent up ends 146. The blades 145 are positioned between the discs 141, 142 and 143 and the flanges 147 are fastened to the discs. Each of the paddle 50 wheels 140 has a hub 148 with a corrugated circumferential outer face, comprising the crowns 149 and the valleys 149a. The inner ends of the blades 145 extend into openings of the crowns 149. In each of the hubs 148 are indicated the 55 similar journal bearings 150 and 151. Each of the said journal bearings 150 and 151 is connected to its hub 148 by a pair of spiders 152. It will be noted that the journal bearings 150 are positioned at one side of the central disc 143 and adjacent thereto, and that the journal bearings 151 are positioned adjacent to the outer 60 discs 141. It will also be noted that the journal bearings 150 extend a considerable distance into the hubs 148, to avoid the necessity of providing journal bearings on the outside of the paddle 65 wheels. The driving shaft 92 extends through the journal bearings 150 and 151 and is fastened thereto, by the set screws 154.

70 Suction piping 160 for the pump 120 extends into the well 36. Discharge fittings 161 and 162 for the pump 120, are connected by the nipple 164. A line of discharge piping 166 extends from the fitting 161 and a line of discharge piping 167 extends from the fitting 162. Brackets 169 extend from the ridge pole 72 for the upper por-

tion of the discharge piping 167 which latter leads to the controlling lifting bucket 102.

5 A valve 172 is connected to the discharge piping 167 and is indicated having the arm 173. A valve 175 is connected to the discharge piping 166 and is indicated having the arm 176. A link 178 connects the arms 173 and 176. A spring 179 has one end fastened to the link 178 and its other end is fastened to its adjacent splash board 53. A chain 182 has one end fastened to the link 178 and leads over the guide pulley 183, extending from the post 68, the guide pulley 184 extending from one of the posts 67 and the guide pulley 185 extending from the post 68a. The chain 182 is then led out of the housing 15 64 as indicated in Fig. 7.

A flexible tube or hose 185 is detachably connected to the discharge piping 166 adjacent to the housing 64, by means of the couplings 186. The hose 185 extends below the upper level of 20 the stream 190.

25 A pair of chains or ropes 188 have one end each fastened to the front corners of the float 20, and their other ends are fastened to buoys, not shown, or to other convenient supports

30 Referring particularly to Fig. 7, a water supply system is shown and which may be used for the usual purposes and also for an irrigating plant. In said Fig. 7 a running stream is shown at 190 and a hill or mountain is indicated at 191. An elevated reservoir, storage tank or cistern 200 is shown in the top portion of the hill or mountain 191. Discharge piping 202 having the 35 valve 203 extends from the lower portion of the reservoir 200, and provides water for the usual water supply or for an irrigating system. An outlet pipe 204 having the valve 205 extends from the bottom of the tank 200 for cleaning purposes.

40 A stand pipe 206 extends from the ground 207, and in this instance the lower end of the pipe 206 is filled with concrete 208 for stability and for preventing leakage. The stand pipe 206 is provided with the steps 209 constituting a ladder. Guy ropes 210 extend from the stand pipe 206 to the ground in the usual manner. The said stand 45 pipe is provided with the guide rollers 212, 213, and 214 adjacent to its lower end and the guide roller 215 adjacent to its top end. The chain 182 after it leaves the housing 64 is led over the guide rollers 212, 213, 214 and 215 to the upper portion 50 of the said stand pipe. An overflow pipe 216 extends from the top end of the stand pipe 206. A controlling tank 217 having the small vent opening 218 in its bottom wall is suspended from the upper end of the chain 182. The overflow 55 pipe 216 extends over the tank 217 when the latter is in its raised position as indicated in Fig. 7. From the lower end of the stand pipe 206 extends the supply piping 220 which leads to the upper end of the reservoir 200.

60 To operate the water motor it is anchored or moored in a running stream, by means of the chains or ropes 188 and buoys, not shown, or other fastening means. The movable parts of the motor are positioned as indicated on the 65 drawings.

The flow of the stream in this exemplification is in the direction of the arrow A, Fig. 1 and enters the channels 35 after passing the converging walls 32, whereby the speed of the flow of 70 the water is increased. The running water leaves the channels 35 through the outlet openings 35a. The impingement of the running water against the blades 145 of the paddle wheels 140 turn the latter in the direction of the arrow B, Fig. 6, 75

By this means the pinion 139 is turned. The spur gear 138 turns with the said pinion and thereby the worm shaft 131 turns. The crank shaft 125 turns with the worm shaft 131 through 5 the interposed gears, and thereby the power pump 120 is operated. Water is drawn from the stream through the suction piping 160 and discharged from the pump through the discharge piping 166 and 167. The discharge piping initially directs 10 the water discharged from the pump 120 into the top end of the stand pipe 206. The water is led from the stand pipe 206 to the elevated reservoir 200 and is discharged from the latter through the piping 202 for a water supply, irrigating system or for any other useful purpose. When the stand pipe 206 and the reservoir 200 are full, the water overflows through the overflow piping 216 and enters the controlling tank 217. When the tank 217 is full of water it descends and the 15 chain 182 is pulled in the direction of the arrow C, Figs. 3 and 7. The water in the tank 217 slowly escapes therefrom through the opening 218. With the descent of the tank 217 the discharge valve 175 of the discharge piping 166 is 20 closed, and the discharge valve 172 of the discharge piping 167 is opened, and water flows from the suction piping 160 through the pump 120 and the discharge piping 167. By this means the controlling lifting bucket 102 is filled and thereby 25 lowered.

The chain 110 is now pulled in the direction of the arrow D, Fig. 3 and the journal boxes 85 are pulled upwardly and guided in the guides 86. At the same time the pinion 139 rolls up on the 30 spur gear 138 and remains in mesh therewith. With the raising of the journal boxes 85, the driving shaft 92 is also raised and the paddle wheels 140 are elevated clear of the streams of water in the channels 35 and the pump 120 is 35 stopped. When the controlling lifting bucket 102 lowers the water therein slowly runs therefrom through the controlling valve 112, and flows into the stream through the well 36. The rate of flow from the bucket 102 is controlled by the 40 controlling valve 112. The valve 112 can be adjusted so that the controlling lifting bucket 102 is drained at a predetermined time to enable the pump 120 to resume operations. When the bucket 102 has been discharged of its water the 45 paddle wheels 140 descend by gravity and are again positioned in the streams of water in the channels 35 to again start operations. When the tank 217 is empty it automatically rises by the tension of the spring 179, and the chain 182, 50 moves in a direction opposite to the arrow C. By this means the link 178 is pulled in a direction opposite to said arrow C, and the valve 175 is opened and the valve 172 is closed. With the 55 operation of the paddle wheels 140 the pump 120 again draws water through the suction piping 160 and discharges said water through the discharge piping 166 to again enter the stand pipe 206. The water motor in this specification is described as furnishing water for water supply, but 60 it will be noted that the motor can be used for furnishing energy for various purposes.

Referring particularly to Figs. 1 and 3, attention is directed to the curved deflecting strips 51 and 51a, which deflect the streams of water 65 in the channels 35 to impinge against the paddle wheels 140 between their discs 141 and 142 and against the blades 145 of said paddle wheels.

It will be noted that the flexible hose 185 enables the float 20 to rise and lower with variations in the tide of the stream, and to be prop-

erly positioned with various directions of the flow of the stream.

Various modifications may be made in the invention and the present exemplification is to be taken as illustrative and not limitative thereof. 5

Having described my invention I claim:

1. The combination of a float positioned in a running stream, a paddle wheel journaled in the float and normally immersed in the stream, a pump supported on the float, suction piping for 10 the pump to draw water from the stream, connections between the paddle wheel and the pump, a chain having one end thereof in connection with the paddle wheel, a controlling lifting bucket suspended from the other end of the chain, an outlet for the bucket, discharge piping for said pump leading to said bucket, a valve in said discharge piping and automatic means to open and close 15 said valve.

2. The combination of a float in a running stream of water, a pair of curved guides each having one end fastened to the float, a journal box in 20 slidable contact with each guide, a driving shaft journaled in the journal boxes, a pair of paddle wheels fastened to the driving shaft normally 25 positioned in the stream and actuated thereby, a pinion fastened to the driving shaft, a second shaft journaled in the float, a spur gear fastened to the second shaft and in mesh with said pinion, a pump supported in the float, suction piping 30 leading from the pump into said stream, discharge piping for the pump, connecting means between the second shaft and said pump and automatic means to lift the paddle wheels clear 35 of the stream, said pinion remaining in mesh with said gear during the lifting of said wheels and said paddle wheels lowered by gravity.

3. The combination of a paddle wheel adjustably positioned in a running stream of water to 40 rotate said wheel, a pump to pump water from said stream, connections between the paddle wheel and said pump to operate the latter, suction piping for said pump leading from said stream, a controlling lifting bucket suspended adjacent to 45 the pump, discharge piping leading from said pump to said lifting bucket, said lifting bucket being connected with said paddle wheel to lift the latter out of the stream when said bucket has been pumped full of water, means to empty said 50 bucket and means to stop the flow of water into said bucket from said discharge piping at a predetermined time, said paddle wheel descending into said stream when said bucket has been emptied of its water. 55

4. The combination of a paddle wheel positioned in a running stream of water, a pump adjacent to the paddle wheel, connections between the wheel and pump to rotate the latter, suction piping for the pump, discharge piping extending 60 from the pump, a valve in the discharge piping, a spring having one end fixed and its other end in connection with the valve, a stand pipe, said discharge piping leading to the stand pipe, an overflow pipe extending from the top end of the 65 stand pipe, a chain having one end in connection with said valve and leading to the upper end of the stand pipe and a controlling tank having a small opening in its bottom wall suspended from the other end of said chain and positioned below 70 the overflow pipe and when full descending to close said valve, said tank being raised when empty by the tension of said spring and said spring simultaneously opening the valve in the 75 discharge piping.

5. The combination of a paddle wheel adjustably positioned in a running stream to rotate said wheel, a pump to pump water from the stream, connections between the paddle wheel and the pump to operate the latter with the rotations of the paddle wheel, suction piping for the pump, discharge piping for the pump, a valve in the discharge piping, a spring having one end fixed and its other end in connection with said valve, a chain with one end in connection with said paddle wheel, a controlling lifting bucket suspended from the other end of the chain, and a controlling outlet valve extending from the bottom wall of the bucket, said bucket positioned under the outlet end of the discharge piping and descending when filled with water from the discharge piping and lifting the paddle out of the stream and said spring simultaneously closing the valve in the discharge piping.
- 20 6. The combination of a pair of paddle wheels adjustably positioned in a running stream of water, to turn the paddle wheels, a pump to pump water from the stream, connections between the paddle wheels and the pump to operate the latter, suction piping for the pump leading from the stream, two lines of discharge piping independent of each other extending from the pump, a stand pipe, one line of said discharge piping leading to said stand pipe, automatic means to stop the flow of water in the discharge pipe leading to the stand pipe when the latter has been pumped full of water, a chain having one end thereof in connection with said paddle wheels, a controlling lifting bucket suspended from the other end of the chain and means to empty the bucket, the second line of discharge piping leading to the bucket, said bucket when full descending and lifting the paddle wheels out of the stream, said wheels descending by gravity when said bucket has been emptied.
- 25 7. The combination of a paddle wheel adjustably positioned in a running stream, a pump to pump water from the stream, connections between the paddle wheel and the pump to operate the latter with the rotations of the paddle wheel, suction piping for the pump leading from the stream, two lines of discharge piping independent of each other extending from the pump, a valve in each line of discharge piping, a link connecting said valves, a spring having one end connected to said link and its other end fixed adjacent thereto, a stand pipe, one line of said discharge piping leading to said stand pipe, an overflow pipe extending from the top end of the stand pipe, a chain extending from said link to the upper end of the stand pipe, a controlling tank suspended from the other end of said chain and positioned below the overflow piping and when

full lowering to close the valve in the discharge piping leading to the stand pipe and to open the valve in the other or second line of discharge piping, a chain in connection with the paddle wheel, a controlling lifting bucket suspended from the other end of the latter chain and a controlling outlet valve for the lifting bucket, the second line of discharge piping leading to said bucket, said bucket when full descending and lifting the paddle wheel out of the stream and said spring closing the valve in the second line of discharge piping.

8. The combination of a float, parallel longitudinal side walls for the float, a buoyant chamber in the float, longitudinal side walls for the chamber, converging front walls extending from the side walls of the chamber, channels formed by the side walls of the float and the adjacent walls of the buoyant chamber, a pair of paddle wheels journaled on the float extending into said channels, an outlet opening for each channel at the rear end of the float and deflecting strips in each of said channels extending from the side walls of the buoyant chamber and the side walls of the float.

20 9. The combination of a float in a running stream, parallel longitudinal side walls for the float, a buoyant chamber in the float, longitudinal side walls for the chamber, converging front walls extending from the side walls of the chamber, channels formed by the side walls of the float and the walls of the buoyant chamber, an outlet opening for each channel at the rear end of the float, deflecting strips for each of said channels extending from the side walls of the buoyant chamber and the bottom and the side walls of the float, a shaft journaled in the float, a pair of paddle wheels having blades fastened to the shaft and extending into said channels, blades for the paddle wheels, the streams of water when flowing through the channels increasing in speed and deflected against the blades of the paddle wheels.

25 10. The combination of a float, a pair of elongated journal boxes secured in the float, a shaft, journaled in said journal boxes, a paddle wheel fastened to each of the opposite end portions of the shaft, a hub for each paddle wheel, a pair of journal bearings for each hub, one of the said journal bearings adjacent to the outer end of its hub and the other journal bearing adjacent to the middle portion of its hub, the end portions of said shaft fastened to said journal bearings, each of the journal boxes extending into the hub of its adjacent paddle wheel, a pump in the float and connections between said shaft and said pump.

GEORGE W. JACOBS.
